TOY IRON

Duane E. Spengler, West Falls, N.Y., assignor to Fisher-
Price Toys, Inc., East Aurora, N.Y., a corporation of
New York

Filed Feb. 28, 1967, Ser. No. 5,984

Term of patent 14 years

(Cl. D34—15)

FIG. 1.

FIG. 2.

FIG. 3.

FIG. 4.

FIG. 1 is a side elevational view of a toy iron showing my new design;

FIG. 2 is a top plan view thereof;

FIG. 3 is a front view thereof; and

FIG. 4 is a rear view thereof.

I claim:

The ornamental design for a toy iron, substantially as shown.
